UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE

TYPEWRITING MACHINE.

Original application filed September 9, 1919, Serial No. 322,630. Divided and this application filed November 4, 1920. Serial No. 421,641.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to collating tables 10 for typewriters, and is a division of co-pending application, Serial No. 322,630, filed September 9, 1919.

This device is illustrated as applied to a typewriter, more particularly a typewriter 15 having a shiftable platen, as in the above-named co-pending application, but it will be apparent from the description that the table may be applied to any typewriter.

The device comprises a collating table, and 20 is provided with members slidable thereon and forming side and end-gages. The table is also provided with a reinforcing strip running lengthwise along its rear face. Slidable members are provided with portions 25 embracing the top of the table and the reinforcing strip in the rear, the strip acting as a guide preventing longitudinal movement, or movement away from the back of the table. The slidable members are provided 30 also with cam spring-clips adapted to clamp the members in position or release them for lateral movement.

Other features and advantages will hereinafter appear.

35 In the accompanying drawings,

Figure 1 is a perspective view of the device applied to a typewriting machine.

Figure 2 is a vertical cross-section of Figure 1 taken between the slide-members and 40 looking toward the left.

Figure 3 is a rear view of a slide-member, showing the cam-clip and projecting finger.

Figure 4 is a section through the cam-clip, the clip being in open or ineffective position, to allow the slide-member to be moved.

Figure 5 is a similar view with the clip in closed position, preventing the slide-member from being displaced laterally.

The platen 10 is provided with an axle 11 which is journaled in the ends 12 and 13 of the shift-frame which may be carried in part by the usual arms 14. A record-sheet 15 may be inserted around the platen 10 by carrying it up from the rear, so that it engages pressure rolls 16 and 17. The platen 55 may be rotated by the usual finger-wheel 20, or line-space lever 21, to advance the record-sheet past the printing point, indicated diagrammatically by the type-bar 22, and upwardly. Before the record-sheet 15 reaches the top of the platen it is guided beneath fingers 23 having slightly out-turned ends 24 to catch the end of the record-sheet, the fingers being resilient and supported on collating table 25, which stands above the platen. To give the outer ends of the fingers a little extra stiffness, one margin may have a narrow turned-up edge 26 (Figure 3), which diminishes toward the outer end.

The collating table 25 is shown as provided with slidable members 30 upon which the spring fingers 23 may be adjustably mounted by screws 31 threaded into the extensions 32 of the members 30 and passing through the slots 33 in the fingers, the body 34 of the fingers 23 being U-shaped in cross-section to fit around the extensions 32. It will be seen that the extensions 32 are in the form of plates secured on faces of the portions or members 30 which lie at the rear of the collating table 25. The members 30 may comprise a side-gage 36 and a leading-end-gage 37, each formed from the turned-up edge of the sheet-metal of which members 30 are made. The upper-end of each member or gage 30 is bent around behind the table 25 at 38, where it comprises bent-up ears 39, adapted to serve as pivots for finger-pieces 40, said finger-pieces comprising bent-over cam-ends 41 adapted to strike a bar 42 in back of the table 25, the cam 41 extending through the opening 43 in the rear extension 44 of the member 30. Normally the cam 41 is urged against the back of the bar 42 by spring 45 coiled around the pivot-shaft 46, upon which the finger-

piece 40 is journaled in the ears 39 by its ears 47. The bar or plate 42 tends to stiffen the table 25, and comprises a cut-away portion 51 (see Figures 4 and 5) around which the end 52 of the extension 44 of the member 30 is bent.

The table 25 is shown as adjustably fast upon arms 54 by means of screws 55 operating in slots 56. It will be observed that sheets 60 may be adjusted upon table 25, and the latter may be readily adjusted for a height, since the screws 55 stand with their heads at the front of the table. To enable work-sheets to be readily and accurately adjusted to their positions without readjusting the table 25, the body of the table may be provided with ruled lines 61 in the body of the metal at line-space intervals. If desired, the lines 61 may be utilized for offsetting work-sheets one above the other by line-space intervals on observing the lines 61 beyond the margins of the work-sheets. The fingers 23, instead of extending in a straight line below their slots 33, may be offset to one side, thus bringing them substantially at the margin of the record-sheet 15, which may be as narrow as the work-sheet 60. It will be noticed that the side-gages, end-gages, and extensions 44 of the members 30 are so located relatively to each other that they may be stamped from a single sheet of metal and bent into shape. To give the members 30 the necessary guiding at the top, each may include the bent-over portion 38 on each side of the end-gage 37. The end-gages 37 may be so low that when a work-sheet is advanced after being gaged thereagainst, it may be advanced over them.

Variations may be resorted to within the scope of the invention, and portions of the improvements may be used without others.

Having thus described my invention, I claim:

1. The combination with a platen, of a paper-table above the platen, a gage adjustable along the length of the platen upon said table, an extension of said gage behind the table, and a finger upon said extension adapted to yieldingly hold a work-sheet upon the platen and guide it beneath the table.

2. In a front-strike typewriting machine, the combination with a revoluble platen and a paper-table above the platen, of side gages partly embracing said table and adjustable thereacross, a spring mounted-finger-piece upon each gage behind the table adapted to be swung to release the gage, and a resilient finger, extending from the gage to the platen, to detain a sheet upon the platen, when lying beneath the gage.

3. In a front-strike typewriting machine, the combination with a revoluble platen and a paper-table above the platen, of an edge-gage upon said table and comprising an ex-

tension behind the table, ears upon said extension, a finger-piece journaled upon said ears, a cam-extension of said finger-piece adapted to bear against the back of the table, and a spring normally holding the cam-extension effective, said paper-table being provided with a guide to co-operate with the lower edge of the extension of said gage to hold it against movement away from the paper-table.

4. In a front-strike typewriting machine, the combination with a revoluble platen, of a paper-table above the platen, a gage mounted upon said paper-table and comprising a portion extending over the upper edge of the paper-table, said portion being provided at the rear of the paper-table with turned-up ears, a finger-piece comprising ears, an axle for said finger-piece common to said ears, said finger-piece being in the form of a thin piece of metal, and a bent-over extension of said metal to bear against the table to hold the gage, said paper-table and said portion of the gage at the rear of the paper-table being provided with co-operating parts to maintain said portion against movement away from the paper-table.

5. In a front-strike typewriting machine, the combination with a revoluble platen and a collating table above the platen, of an edge-gage upon said table and comprising an extension behind the table, ears upon said extension, a finger-piece journaled upon said ears, a cam-extension of said finger-piece adapted to bear against the back of the table, and a spring normally holding the cam-extension effective, said finger-piece extending above but behind the platen out of the way of work-sheets.

6. The combination with a revoluble platen, of a collating table above the platen, and right and left side gages independently adjustable along said table, each of said side gages being provided with a leading-edge gage and a spring-finger to hold against the platen a record-sheet passing between the collating table and the platen.

7. A gage adapted to lie upon a table comprising a body, an extension bent over behind the table, ears upturned from said extension, a finger-piece journaled in said ears, and a cam-extension of the finger-piece adapted to bear against the table through the opening from which the ears are stamped out.

8. The combination with a revoluble platen and a collating table above it, of resilient fingers adjustably mounted upon the table and adapted to bear against the platen to hold a work-sheet thereon beneath the table, and upturned sides extending part way of the fingers to give stiffness to their outer ends.

9. The combination with a revoluble platen, of a collating table above the platen,

- and right and left side gages independently adjustable along said table, each of said side gages being provided with a leading-edge gage; a portion extending around the 5 upper edge of the collating table and along the back face thereof, and a spring-finger, attached to said portion back of the table and extending forwardly and downwardly, to hold against the platen a record-sheet passing 10 between the collating table and the platen.
10. The combination with a revoluble platen, of a collating table above the platen, right and left side gages independently adjustable along said table, each of said side gages consisting of a single piece of sheet-metal having a flat portion to lie on the front face of the collating table, an upwardly-projecting flange at the side of said 15 flat portion, an extension positioned to lie along the back of the table by bending the sheet-metal to fit around the edge of the table, and a tongue stamped out of the sheet-metal at the bend and turned up to a position 20 perpendicular to the flat portion so as to serve as a leading-edge gage.
11. The combination with a revoluble platen, of a collating table above the platen, right and left side gages independently adjustable along said table, each of said side gages consisting of a single piece of sheet-metal having a flat portion to lie on the front face of the collating table, an upwardly-projecting flange at the side of said 25 flat portion, an extension positioned to lie along the back of the table by bending the sheet-metal to fit around the edge of the table, and a tongue stamped out of the sheet-metal at the bend and turned up to a position 30 perpendicular to the flat portion so as to serve as a leading-edge gage, and clamps individual to said side gages to hold the same in adjusted position on said table.
12. The combination with a revoluble platen, of a collating table above the platen, right and left side gages independently adjustable along said table, each of said side gages consisting of a single piece of sheet-metal having a flat portion to lie on the 35 front face of the collating table, an upwardly-projecting flange at the side of said flat portion, an extension positioned to lie along the back of the table by bending the sheet-metal to fit around the edge of the table, and a tongue stamped out of the sheet-metal at the bend and turned up to a position 40 perpendicular to the flat portion so as to serve as a leading-edge gage, a clamping member mounted on said extension to press 45 against the back of said table, and guiding means for the end of said extension to hold the extension firmly in position when the clamping member is pressed against the back 50 of the table.
13. The combination with a revoluble platen, of a collating table above the platen, and right and left side gages independently adjustable along said table, each of said side gages being provided with a device to hold it in adjusted position and consisting of a 55 single piece of sheet-metal having a flat portion to lie on the front face of the collating table, an upwardly-projecting flange at the side of said flat portion, an extension positioned to lie along the back of the table by bending the sheet-metal to fit around the upper edge of the table, a tongue stamped out of the sheet-metal at the bend and turned up to a position 60 perpendicular to the flat portion so as to serve as a leading-edge gage, and ears stamped out end to end in the extension at the back of the table and bent back to the right and left, respectively, to support the holding device so that the latter may engage the back face of the table through the opening formed by bending back said ears, said device comprising a member pivotally supported in said ears, a spring tending to move said member to holding position and a finger-piece to withdraw said member from holding position to enable the gage to be shifted along the collating table.
14. The combination with a revoluble platen, of a collating table above the platen, a bar secured to the rear face of the collating table and parallel to the upper edge thereof, said bar being cut away at its lower edge to form a ledge spaced from the back 65 face of the table, and right and left side gages independently adjustable along said table, each of said side gages consisting of a single piece of sheet-metal having a flat portion to lie on the front face of the collating table, an upwardly-projecting flange at the side of said flat portion, an extension positioned to lie along the back of the table by bending the sheet-metal to fit around the edge of the table, and a tongue stamped out of the sheet-metal at the bend and turned up to a position 70 perpendicular to the flat portion so as to serve as a leading-edge gage, the end of said extension being bent around said ledge and between the same and the rear face of the table to hold the gage on 75 the table.
15. The combination with a revoluble platen, of a collating table above the platen, a bar secured to the rear face of the collating table and parallel to the upper edge 80 thereof, said bar being cut away at its lower edge to form a ledge spaced from the back face of the table, and right and left side gages independently adjustable along said table, each of said side gages consisting of a single piece of sheet-metal having a flat portion to lie on the front face of the collating table, an upwardly-projecting flange at the side of said flat portion, and an extension positioned to lie along the back of 85 the table.

the table by bending the sheet-metal to fit around the edge of the table, the end of said extension being bent around said ledge and between the same and the rear face of the table to hold the gage on the table.

16. The combination with a revoluble platen, of a collating table above the platen,

right and left side gages independently adjustable along said table, and a leading-edge gage associated with each of said side gages.

ALFRED G. F. KUROWSKI.
